WARP TENSIONING CONTROL

Archibald Taylor Guild, Saratoga Springs, N. Y.,
assignor to Van Raalte Company, North Tonawanda, N. Y.

Application April 13, 1934, Serial No. 720,464

6 Claims. (Cl. 242—131)

The present invention relates to a thread tensioning device for use in conjunction with the direct winding of a warp beam and more particularly to a thread tensioning device wherein the tension upon the thread being wound upon the beam can be changed within a given range of tension.

It has been the practice heretofore to employ tensioning discs in conjunction with the winding of thread such as real and artificial silk threads from spools or packages upon a beam, thread being delivered from cross wound packages, cops or spools whereby the thread runs freely and is delivered rapidly, passing through eyelets and being engaged in tensioning discs, the amount of tension of any particular tensioning disc being generally controlled by means of weighted washers.

In the employment of this prior method where the discs are not properly weighted, the threads tend to run generally upon one portion of the disc producing grooves therein should the operation continue for sufficient periods of time without causing rotation of the tensioning discs. Further, when the discs fail to rotate, loose particles of thread such as slubs of yarn and fluff pass to the needle bar of the knitting machine or into the fabric creating imperfections therein.

Where grooves have been worn in the discs there is substantially little tension upon the individual threads engaging the grooved discs and where automatic stop motion is used in conjunction with the warp beam winding excessive stoppage of the machine is produced due to the decrease in tension of the particular threads.

An object of the present invention is to produce means whereby tensioning of the individual thread delivered from packages, cops or spools of thread may be subjected to the desired tension and a tension wherein the tensioning discs are caused to rotate substantially continuously during the warp winding operation thus eliminating the disadvantages inherent in the tensioning devices heretofore employed.

45 In the drawings:

Fig. 1 is a fragmentary plan view of a creel showing the tensioning device attached thereto.

Fig. 2 is a section partly in elevation of a fragmentary portion of a creel showing threads passing from packages of thread to the improved tensioning device.

Fig. 3 is a side elevation of the means for simultaneously changing the angle of thread engagement of a plurality of the tensioning discs.

55 Fig. 4 shows an enlarged view of the improved

tensioning disc attached to means adjacent an eyelet bar of the creel for varying the tension of threads.

Fig. 5 is a cross sectional view taken on the line V—V of Fig. 4.

Fig. 6 is an enlarged fragmentary view of an eyelet bar of a creel showing another form of the improved tensioning device attached thereto; and

Fig. 7 is a cross sectional view taken on the line VII—VII of Fig. 6.

Referring more particularly to the drawings, a creel is indicated generally at 10 provided with longitudinally extending members such as angle irons 11 to which spindles 12 are attached. Packages, cops or spools of thread 13 are carried upon spindles 12 in the usual manner and thread is delivered from the packages 13 and passes through eyelets 14 provided in the eyelet bar 15 extending longitudinally of the machine and adjacent the front thereof, an eyelet bar being provided for each series or row of spindles and thread packages and being provided with a plurality of eyelets 14 corresponding in number to the number of spindles or thread packages carried in the row.

The thread 16 after passing through eyelets 14 in eyelet bar 15 is engaged, as is well shown in Figs. 4 and 5, between the upper and lower tensioning discs, such as 17 and 18 and thereafter passes (Fig. 2) through an eyelet 19 provided in guide bar 20 extending outwardly from the creel 10 after passing through heddles (not shown) engaging the electrode bar 21 as more fully described in a co-pending application S. N. 674,938, now Letters Patent No. 2,017,008 dated October 8, 1935, dealing with an improved method of direct winding of a warp beam from a creel provided with automatic stop motion.

In the form of the invention as shown in Figs. 4 and 5, a tensioning disc supporting member 35 is spaced from the outwardly extending flange 26 of eyelet bar 15 and supported upon and pivotally attached at 37 to the bar or strap member 36. In order that the tensioning disc support member may be moved relatively with respect to the creel 10, member 35 is pivotally attached to flange 26 at 38, pivot points 37 and 38 being made by means of bolts and nuts as shown or by other well known means. The disc supporting member 35 extends longitudinally of the creel and adjacent the front thereof as shown in Figs. 1 and 3, being supported by a plurality of strap members 36 and 36', etc., and bearing thereon a plurality of post members 23, each post engaging a thread tensioning device. A plurality of disc supporting members are provided for each creel 55

and in general there are as many of such members as there are rows of spindles. By positioning post member 23 upon disc supporting bar 35 at a point offset or out of line with respect to eyelet 14 sufficient angle of engagement of thread 16 with tensioning discs 17 and 18 is provided for so that by movement of the disc supporting member 35 in the direction of the arrows toward either the position A or B the angle of engagement is changed and the speed of rotation of the discs correspondingly changed, an intermediate position being found where a minimum of rotation or substantially no rotation occurs. In general, moving the disc supporting bar in the direction of arrows A or B will speed up the rate of rotation of the disc to a maximum while at a particular point of movement a position of minimum speed of rotation or no rotation will be produced depending upon the type of thread engaged by the tensioning disc. By placing eyelet 14 toward the warp end of creel 10 a snubbing action of thread 16 is obtained on eyelet 14 and post 23 while a friction engagement is obtained by passing the thread between discs 17 and 18.

In order to change the angle of engagement of a plurality of threads, a plurality of tensioning discs are attached to the disc supporting member 35 and may be moved simultaneously by effecting movement of the disc supporting member 35 or, as shown in Fig. 3, a plurality of disc supporting members 35, 35', etc., may be attached by means of the end bars 44 and 45 which are threaded at their upper and lower ends and a loose fitting engagement made with members 35, 35', etc., by means of nuts 46 and 47. Thus, upon movement of end bar 44 either to left or right, as shown in Fig. 3, movement of the entire group of tensioning discs supported upon the tension support bars 35, 35', etc., is correspondingly effected.

It will be seen from the above description that a device and method whereby the tension of threads leaving thread packages on a creel is provided and whereby a plurality of threads engaged by tensioning discs may simultaneously have their angle of engagement changed with respect to the tensioning disc and effect the proper tensioning thereof by causing rotation of the tensioning discs with attendant advantages pointed out above.

This movement of the tensioning discs changes the snubbing action on the thread as well as the friction tension due to engagement of upper and lower discs 17 and 18 and hence the necessity of using weighting washers upon each individual device is substantially eliminated.

In another form of the invention shown in Figs. 6 and 7, I have provided tensioning discs attached adjacent but offset from eyelets formed in the eyelet bars and positioned upon an outwardly extending flange of the eyelet bar. The tensioning device comprises post member 23 formed from the screw headed bolt 24, surrounded by a porcelain or other smooth surfaced sleeve 25, attached to outwardly extending flange 26 of eyelet bar 15 by means of nut 27, leather or other fabric type washers 28 and 29 being provided at the top and bottom of porcelain sleeve 25. The tensioning disc proper is formed of the upper and lower tensioning discs 17 and 18 which are formed with an apertured center portion and having a curved or cup-shaped bottom portion. In accordance with my invention, the tensioning disc is offset from the cooperating eyelet, as shown in Fig. 6, whereby thread 16, passing from a package of thread through eyelet 14 in eyelet bar 15

extends angularly from the eyelet and is engaged by tensioning discs 17 and 18, thereafter passing through eyelet 30 positioned in the upwardly extending flange portion 31 of strap member 32 pivotally attached to flange 28 of eyelet bar 15 by means of bolt and nut members 24 and 27 respectively. In order to prevent grooving of the tensioning disc, movement of thread passing between upper and lower tensioning discs 17 and 18 should cause rotation of the discs and eliminate the necessity of adding weighted washers thereon. I have provided means for changing the angle of engagement of the thread with tensioning discs by moving strap member 32 as indicated by arrows in Fig. 6, movement of the member in direction C or D varying the angle of engagement of the thread and in general changing the speed of rotation of the discs, an intermediate position being reached wherein a minimum of rotation or no rotation occurs. By moving strap member 32 to a position at which rotation of upper and lower tensioning discs is induced proper tensioning of the threads sufficient to support a heddle away from contact of the electrode bar 21 with inadvertent stoppage of the machine is obtained while at the same time grooving of the discs is prevented and the formation of slubs eliminated. By providing for change of the angle of engagement with the thread the tensioning discs are capable of properly tensioning threads of varying diameter, texture and weight without the necessity of providing weighting means upon the disc.

It will be seen that by providing the porcelain eyelet 14 at a point farther toward the front of the creel, i. e., toward the warp than the center of the tensioning disc, yarn passing therethrough around the porcelain port member 23 and between the discs 17 and 18 is subjected to a combined tension consisting of a snub tension and a friction tension, the snub being caused by the eyelet and post, and friction by the weight of the upper and lower discs squeezing the thread.

By moving bar 32, eyelet 30 may be set so that the angle of engagement of thread 16 between upper and lower discs is such as to produce substantially continuous rotation of these discs thereby preventing the release of the friction tension with production of slack thread and a consequent false stop or the production of an uneven warp. Further, continual rotation of these discs prevents lodgement of bits of lint, slubs, dirt, etc., between the discs with release in tension.

I have obtained good tension and maximum rotation of the discs with a thread angle of about 105°. By moving the bar in the direction of the arrows toward either C or D, the speed of rotation of the discs decreases and finally ceases. By providing for adjustment of this angle of engagement, the device is adaptable for use with a variety of types and sizes of yarn as well as a wide adjustment of speed of rotation.

I claim:

1. In a device for delivering thread under tension, a creel for holding a plurality of packages of thread, an eyelet bar having eyelet guides for guiding threads passing from the packages, tensioning means comprising an upper and lower disc adapted to receive a thread therebetween, one of said discs being rotatable, a post attached to said eyelet bar and engaging said means, a bar member pivotally attached to the post, and means on said bar for engaging a thread passing from said discs.

2. In a device for delivering thread under tension, a creel for holding a plurality of packages of thread, an eyelet bar having eyelet guides for guiding threads passing from the packages, tensioning means comprising an upper and lower disc adapted to receive a thread therebetween, one of said discs being rotatable, a post attached to said eyelet bar and engaging said means, a bar member pivotally attached to said post at one end, and thread engaging means upon its other end for engaging a thread passing from said discs.

3. In a device for delivering thread under tension, a creel for holding a plurality of packages of thread, an eyelet bar having eyelet guides for guiding threads passing from the packages, tensioning means comprising an upper and lower disc adapted to receive a thread therebetween, one of said discs being rotatable, a post attached to said eyelet bar and engaging said means, a bar member pivotally attached at one end to the post, the other end having an upwardly extending flange thereon, and an eyelet in said upwardly extending flange for engaging a thread passing from said discs.

4. In a device for delivering thread under tension, a creel for holding a plurality of packages of thread, an eyelet bar having eyelet guides for guiding threads passing from the packages, a post mounted upon said eyelet bar, upper and lower tensioning discs engaging said post and adapted to receive a thread therebetween, one of said discs being rotatable, a bar member pivotally attached at one end to the post, the other end having an upwardly extending flange thereon, and an eyelet in said upwardly extending flange for engaging a thread passing from said discs.

5. In a device for delivering thread under ten-

sion, a creel for holding a plurality of packages of thread, an eyelet bar having eyelet guides for guiding threads passing from the packages, a post attached to the eyelet bar, tensioning means rotatably connected to said post comprising upper and lower discs adapted to receive thread therebetween, one of said discs being rotatable, a bar member pivotally attached to the post, and thread engaging means upon the end of said bar for engaging a thread passing from said tensioning means whereby the angle of engagement of a thread with the tensioning discs can be continuously varied from an angle of minimum tension upon a thread through an angle of maximum tension thereon.

6. In a device for delivering thread under tension, a creel for holding a plurality of packages of thread, thread guiding and tensioning means associated with said creel and comprising a horizontally extending bar of angular cross section disposed adjacent said creel, said bar having a vertically disposed leg having a plurality of thread guiding eyelets therein and a horizontal leg at the lower edge of said vertical leg and extending in a direction away from said creel, frictional thread tensioning means associated with each eyelet and comprising coaxial rotatable disc-like elements with facing convex surfaces, means for supporting said tensioning means on the horizontal leg of said angle bar for rotation about a vertical axis and with the abutting surfaces of said tensioning means in horizontal alignment with its associated eyelet whereby a thread from said eyelet may pass between said rotatable elements, and pivotal means for varying the angle between the entering and leaving portions of said thread in said friction means.

ARCHIBALD TAYLOR GUILD.
